UNITED STATES PATENT OFFICE

2,511,759

OIL WELL FORMATION TESTER

Philip S. Williams, Tulsa, Okla., assignor to
Standard Oil Development Company, a corpora-
tion of Delaware

Application April 23, 1948, Serial No. 22,922

6 Claims. (Cl. 166—1)

1

The present invention relates to an improved type of formation tester to be employed in oil wells. In accordance with this invention an apparatus is provided having a motor operated to work pumping means associated with an inflatable packer and a sample containing chamber, to permit sealing off a desired portion of an oil well and to permit withdrawing fluid from this portion of the well into the sample chamber.

In drilling an oil well, the well is maintained full of a fluid such as drilling mud. This is necessary in order to maintain a sufficiently high hydrostatic pressure in the well to prevent the uncontrolled escape of natural fluids in the earth. However, the necessity for maintaining the well full of fluid during the drilling complicates the removal of natural fluids from the earth for sampling purposes. Thus, in order to remove a sample of fluid from a particular stratum of the oil well, it is first necessary to reduce the hydrostatic pressure of drilling mud on this stratum sufficiently to allow the escape of the fluid from the stratum and then in some way to remove the fluid extracted to the surface of the earth. The technique by which this is done is called formation testing and the apparatus employed for the purpose is called formation testing apparatus. It is this field with which the present invention is concerned.

Formation testing apparatus has been proposed of such a nature that an inflatable elastic packer is used to seal off the well at a desired point so as to permit reducing the hydrostatic pressure at the point sealed off without reducing the hydrostatic pressure throughout the well. However, an apparatus of this type presently known to the art is of rather complicated construction and is not flexible in the sense that it cannot be used under a variety of conditions. For example, it is presently necessary to employ one type of formation tester in combination with a drill string or to employ a different type of tester in combination with a coring bit or even to employ a tester necessitating removal of all drilling apparatus from the well. Therefore, it is a principal object of this invention to provide an improved form of elastic packer formation tester which may be used under any of the circumstances indicated above.

In accordance with this invention a compact formation tester is provided suitable for lowering down a drill string and if desired through a core bit. Alternatively the tester may be employed by removing the drill pipe from the well. The apparatus of this invention comprises an elastic packing means associated with suitable pumping means so as to permit sealing off the well at any desired point and so as to permit pumping samples of fluid through a porous section of the elastic packer to a suitable sample-receiving cham-

2

ber. The apparatus may be supported by a cable or by the drill string. As indicated, therefore, the apparatus of this invention is characterized by simplicity of construction, flexibility of use, and ease of sampling.

A preferred form of the apparatus of the present invention is illustrated in the attached Figs. 1 and 2. These figures are related as Fig. 1 is simply the upper continuation of Fig. 2. In these figures, the numeral 1 identifies a well hole which has been dug in the earth. It is to be understood that this hole is normally filled with fluid such as drilling mud. For simplicity no fluid has been shown in the drawings in the hole 1. The apparatus illustrated is suitably supported in the hole by means such as the cable 2. As will become apparent, in place of the cable 2, a drill string or equivalent supporting means may be employed. The cable 2 is of the conventional type suitable for sustaining the weight of the apparatus and at the same time suitable for protecting electrical conductors contained in the cable. In the drawing, the cable 2 is shown to be terminated by a sample-receiving chamber indicated by the numeral 9. This sample chamber supported by the cable 2 serves in turn to support the remaining components of the apparatus. Thus a connecting member or support 50 is provided to connect the sample chamber 9 with the motor 25. The motor 25 in turn is connected to the pump 7 by the connecting and supporting means indicated as rods 26. Similarly, a second pump 15 is connected to pump 7 by supporting means 27 and the pump 15 is connected to the elastic packer by the supporting rod 28. As illustrated, the motor 25 is an electric motor suitably supplied with electricity through a conductor leading from the cable 2, either through or around the sample chamber 9. The motor 25, 40 is directly connected to the pumps 7 and 15 through shaft 29. The elastic packer indicated by the numeral 3, as illustrated in the inflated position, is essentially an oval-shaped bag. It will be noted that a portion of the bag, comprising a narrow circumference, consists of a double walled space identified by the numeral 51. While all portions of the packer except the circumference of the double walled portion of the packer are of non-porous material, the portion of the 50 packer comprising the circumference bounding the space 51 is of porous material. This porous section of the packer is indicated by the numeral 52. In fabricating a packer such as that illustrated, it is convenient to employ rubber, although cloth or wire fabric may be employed if desired. Similarly, the porous section of the packer, that is, section 52 may comprise a porous type of rubber. Suitable porous rubber is now commercially available. In the event that the 55 porous section of the packer 52 and the re-

mainder of the packer is made of rubber, the fabrication of the packer is quite simple. The inner portion of the double walled space indicated by the numeral 53 may be composed of the same material as the remainder of the packer, but it should be noted that the inner portion 53 is not porous. Therefore, the elastic packer illustrated in the drawings comprises an inflatable packer having a portion of the packer made as a double walled section. The exterior of the packer comprising the outer surface of the double walled section is porous, while the other parts of the packer are non-porous. It is apparent that fluids may be allowed to enter the double walled section of the packer through the outer porous circumference of the packer. Positioned in the double walled section of the packer are a multitude of pellets indicated by the numeral 5. These pellets may consist of glass, metal, rock or any other desired substance. As will become apparent, the function of these pellets is to fill the double walled section of the packer so that this section cannot be compressed sufficiently to seal it. Thus, the presence of the pellets in the double walled section continuously maintains a porous medium in the packer. It is apparent, of course, that the pellets should be of sufficient size so that they do not pass out of the perforations of the porous area 52 of the packer. A conduit 54, porously sealed to prevent passage of the pellets, is provided to connect the double walled section of the packer with the inlet of pump 7. The outlet of this pump is connected with line 55 which leads to the sample chamber 9. Thus, the operation of pump 7 will tend to cause fluid to be pulled through the perforations of layer 52 of the packer through the double walled section of the packer and conduits 54 and 55 into the sample chamber. A conduit 17, is also provided connecting the innermost part of the elastic packer to the outlet of pump 15. The inlet of pump 15 is connected to the conduit or port 16, which opens into the well. Consequently by operation of pump 15, fluid will be pulled from the well through conduits 16 and 17 into the elastic packer, serving to inflate the packer.

The apparatus heretofore described is complete except for the provision of necessary valves in the various chambers. Thus it is necessary that a valve 10 and a valve 11 be positioned in the sample chamber. The valve 10 is operative to seal the inlet into the sample chamber served by conduit 55, from pump 7. The valve 11 is adapted to seal the outlet of the sample chamber illustrated as port 56 at the upper part of the sample chamber. Both valves 10 and 11 may consist of solenoid operated valves, operated by conductors extending from the cable 2. Valve 11 must be positively actuated, electrically as here suggested, or by some hydraulic connection from one of the pumps. Valve 10, however, could be of the simple check valve type for most applications, though a positively actuated type may be chosen for greater surety of operation. Thus, the operation of these valves is controlled by current supplied through the conductors at the surface of the earth.

The apparatus illustrated in Figs. 1 and 2 having now been suitably identified and described, the operation of this apparatus may be fully understood.

By conventional drilling procedures, a suitable bore hole is drilled in the earth. During the drilling operation by various conventional types of logging, the nature of strata through which

the hole passes are identified. These logging procedures are generally suitable for indicating possible strata suitable for oil production. One such stratum such as the porous zone 4, is illustrated in the drawing. In order to test the fluids, if any, present in this porous formation, the apparatus of this invention is then employed. In the event that a drill string having a core bit has been used to drill the hole, the apparatus may be lowered through the drill string and through the core bit; the core bit, of course, being pulled up from the bottom of the well sufficiently to be above the porous formation to be tested. Alternatively, the drill string and drilling apparatus may be completely removed from the hole. In any event, the apparatus illustrated in Figs. 1 and 2 is lowered into the well so that the double walled section of the packer is adjacent to the porous formation to be tested. While the apparatus is being lowered, the elastic packer is in the deflated position making the packer and the associated equipment sufficiently compact to readily pass downwardly through the drill string or down the well. When the apparatus has been lowered sufficiently so that the double walled section of the packer is adjacent the porous formation to be tested, the packer is inflated by starting the motor 25. At the same time the motor is started, valves 10 and 11 are opened by operation of suitable electrical circuits at the surface of the earth. In actual practice, it is convenient to have the solenoid valves 10 and 11 connected in either series or parallel with the electrical circuit of the motor 25. In this case, it is possible to start the motor and to open valves 10 and 11 by closing a single operating switch at the surface of the earth. For simplicity, these circuits are not shown on the drawings as the circuits themselves do not constitute part of this invention and since they are conventional, simply comprising a suitable switch, a voltage source, and the necessary electrical connections. While pumps 7 and 15 may be either centrifugal pumps or positive displacement pumps, let it be assumed now that pump 15 is a centrifugal pump. The operation of motor 25 will cause both pumps to operate. Pump 15 will draw fluid from the well through port 16 and will pump this fluid through line 17 into the elastic packer causing the packer to be inflated. Simultaneously pump 7 will tend to pull fluid through the perforations of layer 52 of the packer through line 54. This fluid will be pumped through line 55 into the sample chamber through valve 10 and out of the sample chamber through valve 11. The pumping action of pump 15 will continue until sufficient fluid has been pumped into the elastic packer to fully expand it, (i. e. the pump 15 is so chosen that the maximum pressure which it will deliver is such as to properly inflate the packer), thoroughly sealing the well hole adjacent to the packer. This will cause the double walled section of the packer to be tightly forced against the porous formation 4. Therefore, the action of the pump 7 will pull fluid from the porous formation through line 54 and 55 into the sample chamber. The pumping action is continued until the setting of the packer is assured, and until sufficient time has been allowed for fluid to have filled the sample chamber 9. If desired, an auxiliary electrical device 40, may be placed in line 55 to check the nature of the fluid passing through this line. Suitable indicating devices, for example, a resistivity indicator, will give electrical indications at the surface of the

earth, through conductors which may pass through cable 2, of the conductivity of the fluid in line 55. By this means it is possible to insure that the fluid passing through line 55 is not simply drilling mud obtained from the well, but is fluid extracted from the porous formation 4. When the pumping operation described has been continued until a suitable sample has been received in the sample chamber 9, the motor 25 is stopped and the valves 10 and 11 are closed. Again, if desired, these operations may be completed by opening a single switch at the surface of the earth. Stopping the motor 25, will permit the fluid contained in the elastic packer to pass through line 17, through centrifugal pump 15, and out through the port 16 to deflate the packer. The entire apparatus may then be drawn to the surface of the earth and the sample in sample chamber 13 can be examined as desired.

As indicated, if desired, pump 15 as well as pump 7 may consist of a positive displacement instead of a centrifugal pump. In the event pump 15 is a positive displacement pump, it is necessary to include two further valves in the system. These are valves 18 and 20, located in line 17. Valve 18 is a simple check valve, spring loaded to be opened at a given pressure. The valve is adjusted so that this pressure is sufficient to insure full inflation of the elastic packer, but is insufficient to permit rupture of the elastic packer. Thus on operation of the pump 15, fluid will be pumped into the elastic packer until the packer is fully inflated, at which time the pressure in the system will be sufficient to open the relief valve 18. This will permit fluid pumped by pump 15 to bleed off into the well without permitting the packer to deflate. After the sampling operation has been completed, in order to deflate the packer, it is then necessary to open valve 20 in line 17. Valve 20 may again comprise a solenoid operated valve which may be suitably controlled at the surface of the earth by means of conductors passing through the cable 2. For the purpose of simplicity, these conductors have not been illustrated in the drawing. Again, if desired the valve 20 may be connected in an electrical circuit with valves 10 and 11 and the motor 25 so that on closure of a single switch, the motor 25 will be started and valves 10 and 11 will be opened and valve 20 will be closed. Alternatively, when the single switch is opened, the motor 25 is stopped and valves 10 and 11 are closed and valve 20 is opened.

As indicated above, the apparatus illustrated is subject to many refinements and many modifications. An important refinement which may be, or should be, used is the provision of a channel 22 which passes downwardly through the elastic packer to provide a fluid chamber from the space above the packer to the space below the packer. The function of this passageway is to permit equalization of pressure above and below the packer so that no vertical component of pressure is exerted on the elastic packer.

A further modification of importance is to substitute for the cable 2 and the sample chamber 9, a drill string. In this event, the drill string will serve as both a supporting means for the apparatus and as a sample receiving chamber. The line 55 will then pass directly into the drill string without necessity for valves 10 or 11. The support 50 holding the motor may be connected to the drill string by means of a simple pipe cap which may be threaded on to the drill string.

On operation of the pump 25, therefore, fluid will be withdrawn from the porous formation 4, and will be pumped into the drill string toward the surface of the earth. In this event it will be necessary to continue the pumping operation until sufficient fluid has been removed from the formation being tested to completely fill the drill string.

It should also be noted, that the apparatus illustrated in the drawing is diagrammatic and is presented solely to illustrate the nature of this invention. In actual construction, the sample chamber or a drill string is closely coupled to the motor, the pumps, and the elastic packer, so as to provide an integral apparatus extremely compact and comparatively light in weight.

In view of the many modifications of the present invention, the appended claims are to be interpreted broadly, limited only by the true contribution to the art:

What is claimed is:

1. A well testing apparatus for use in a fluid-filled borehole comprising in combination a supporting means provided with a sample-receiving chamber, an inflatable elastic bag fixed to said supporting means, the walls of said elastic bag being constructed of non-porous flexible material, a porous wall attached circumferentially to the exterior of said elastic bag about a middle portion thereof and defining an annular chamber with a portion of the wall of said bag, a first pumping means and a second pumping means carried by said supporting means, a first conduit connecting said annular chamber through said first pumping means to said sample-receiving chamber, and a second conduit connecting the interior of said elastic bag to said second pumping means, said last-named pumping means having an inlet port communicating with said fluid in the borehole.

2. Apparatus as defined in claim 1 in which said supporting means comprises a section of drill pipe whose interior constitutes said sample-receiving chamber.

3. Apparatus as defined by claim 1 in which said sample-receiving chamber is provided with an inlet valve associated with said first conduit and an outlet valve having a port communicating with said fluid in the borehole.

4. Apparatus as defined by claim 1 in which said annular chamber contains pelleted packing material.

5. Apparatus as defined by claim 1 including a channel passing through said elastic bag and communicating with said fluid in the borehole above and below said bag.

6. Apparatus as defined by claim 1 in which said second conduit is provided with a pressure relief valve adapted to vent fluid into said borehole upon attainment of a predetermined pressure within said conduit.
